UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

DRILLING MECHANISM

Application filed May 24, 1923. Serial No. 641,097.

My invention relates to drilling mechanisms, and more particularly to drilling mechanisms of the pneumatically fed type.

An object of my invention is to provide an improved drilling mechanism. Another object of my invention is to provide an improved controlling device for pressure fluid rock drills. A further object of my invention is to provide an improved controlling device for pressure fluid rock drills of the pneumatically fed type whereby the feeding mechanism automatically controls the rotation motor. A still further object of my invention is to provide an improved controlling device for pressure fluid rock drills of the pneumatically fed type responsive to the variations in pressure within the feeding mechanism for automatically controlling the rotation motor. Other objects and advantages of my invention will hereinafter more fully appear.

In the accompanying drawings I have shown for purposes of illustration one form which my invention may assume in practice.

In these drawings,—
25 Fig. 1 is an elevational view, partially in central longitudinal section, of a drilling mechanism embodying my improved device.

Fig. 2 is a transverse section taken on line 2—2 of Fig. 1.

30 In this illustrative form of my invention I have shown a stoper drill of standard form, generally designated 1, including a drilling motor 2 and a feeding mechanism 3. The drilling motor 2, herein of the valveless percussive type, comprises a cylinder 4 having a hammer piston 5 reciprocable therein, in a stepped bore 6, to actuate percussively a drill steel 7 suitably carried in a chuck 7' in the front end of the drilling motor. The feeding mechanism 3 comprises a cylinder 8 having a piston 9 disposed therein and having suitably secured thereto a piston rod 10 terminating in a point 11. Interposed between the drilling motor 2 and the feeding mechanism 3 is a

40 head block 12 having a bore 13 therein forming a continuation of the bore 6 in the cylinder 4, the feed cylinder, head block, and drilling motor parts being suitably held together by said rods 12', in a well known manner.

45 Suitably secured to the head block 12 is also

a handle 15 employed to support the machine during the drilling operation.

An independent pressure fluid actuated rotation motor, generally designated 16, is provided, in this instance, to rotate the drill steel 7 and comprises a pair of intermeshing toothed rotors 17 and 18 disposed in a bore 19 in a casing 19' formed integral with the cylinder 4. The rotor 17 is operatively connected through a shaft 20 disposed parallel with the cylinder 4, mounted in suitable bearings and having a pinion 21 secured thereto meshing with a gear 22 formed on the chuck 7'. Pressure fluid is supplied to the machine through a throttle valve 23 arranged in a boss formed on the head block, from any suitable source of supply, and passes through a port 24 to the feed cylinder 8 and through a port 25 to a constant pressure chamber 26, formed in the head block, and then to the rotation motor, under the control of the automatic control valve, generally designated 27, through a port 28. The valve 27 comprises a conical, or tapered, head 29 which graduates the admission of pressure fluid to the rotation motor, having a cut-away portion, or slot, 30 in its tapered side so that when the valve 27 is seated pressure fluid will pass to the rotation motor. At the opposite end of the valve 27 is a piston head 31 operating in a chamber 32 which communicates with the interior of the feed cylinder 8 by way of a port 33. The chamber 32 at the other side of the head 31 is vented to the atmosphere by way of a port 34 and is suitably closed by a plug 35 through which extends a follower 36 adapted to apply pressure to a spring 37 acting on the head 31 and tending to hold the valve open, the spring pressure in the chamber 32 resisting the main line pressure in the chamber 26 and tending to force the valve to open position. The type of valve shown is used for illustrative purposes only, the particular type of valve used to accomplish the desired result being immaterial.

95 The mode of operation will be clearly apparent from the description given. The point 11 is placed against a suitable abutment, herein the mine bottom, at a proper distance from the working face, the operator holding

the machine in position at this time by means of a handle 15. The throttle valve 23 is then manipulated admitting pressure fluid to the feeding mechanism and to the pressure chamber 26 seating the valve 27, the pressure in the feed cylinder then acting on the left hand side of the head 31 and overcoming the spring 37. Pressure fluid then passes through the slot 30 bringing the rotation motor 16 up to a speed required in normal drilling conditions. As the drilling motor, actuating the steel 7, deepens the hole, the feed cylinder 8 moves upward relative to the piston 9. When, however, a soft spot or cavity is encountered, the cylinder 8 moves rapidly upward relative to the piston 9 tending to stick the drill steel, and in so doing materially reduces the pressure in the chamber 32 and causes the pressure to drop at the left hand side of the piston head 31 of the valve 27 and thereby permit the spring 37 to force the valve open and admit more pressure fluid to the rotation motor, thereby increasing its speed and power to free the drill steel. When normal drilling is resumed the pressure again builds up in the feed cylinder, overcoming the spring 37 and slowing down the speed of the rotation motor.

While I have in this application specifically described one form which my invention 30 may assume in practice, it will be understood that this form of the same is shown for purposes of illustration and that the invention may be modified and embodied in various other forms without departing from its spirit 35 or the scope of the appended claims.

What I claim as new and desire to secure by Letters Patent is:

1. In combination, work performing means including a rotary tool actuating motor, a 40 tool actuated thereby, pressure fluid actuated feeding means for said tool, and means having communication with said feeding means and automatically controlled by pressure changes in said feeding means for controlling said rotary motor.

2. In combination, work performing means including a tool rotating motor, a tool rotated thereby, feeding means for said tool, and means operatively connected to said feeding 50 means and automatically effective when an abnormal rate of feeding movement occurs due to a substantial decrease in the resistance to feeding movement for controlling said tool rotating motor.

3. In combination, work performing means including a tool actuating motor, a tool actuated thereby, pressure fluid actuated feeding means for said tool, and automatic control means having communication with said feeding 60 means and controlled by pressure changes in said feeding means and effective to speed up said tool actuating motor when the pressure in said feeding means is reduced.

4. In combination, work performing means 75 comprising a motor for imparting motion to

a tool, a tool actuated thereby, pressure fluid actuated feeding means for said tool, and means having communication with said feeding means and automatically controlled by pressure changes in said feeding means and effective to speed up said tool actuating motor when the pressure in said feeding means is reduced. 70

5. In combination, a drilling motor, a drill steel actuated thereby, feeding means for said steel, a motor for rotating said steel, and means operatively connected to said feeding means and automatically effective when an abnormal rate of feeding movement occurs due to a substantial decrease in the resistance to feeding movement for controlling said rotation motor. 75

6. In combination, a drilling motor, a drill steel actuated thereby, feeding means for said steel, a motor for rotating said steel, means operatively connected to said feeding means and automatically effective when an abnormal rate of feeding movement occurs due to a substantial decrease in the resistance to feeding movement for controlling said rotation motor. 80

7. In combination, a drilling motor, a drill steel actuated thereby, a motor for rotating said steel, pressure fluid actuated feeding means for said steel, and means having communication with said feeding means and automatically responsive to pressure changes within said feeding means for controlling said rotation motor. 95

8. In combination, a drilling motor, a drill steel actuated thereby, means for rotating said drill steel, pressure fluid actuated feeding means for said drill steel, and means having communication with said feeding means and automatically controlled by pressure changes in said feeding means for controlling said rotation means. 100

9. In combination, a drilling motor, a drill steel actuated thereby, means for rotating said drill steel, pressure fluid actuated feeding means for said steel, and means having communication with said feeding means and automatically controlled by pressure changes in said feeding means for controlling said rotation means. 110

10. In combination, a drilling motor, a drill steel actuated thereby, means for rotating said drill steel, feeding means for said drill steel comprising relatively movable elements, and means operatively connected to said feeding means and automatically effective when an abnormal rate of relative movement between said feeding elements occurs due to a substantial decrease in the resistance to feeding movement for controlling said rotation means. 120

11. In combination, a drilling motor, a drill steel actuated thereby, a pressure fluid actuated rotation motor for said steel, pressure fluid actuated feeding means for said 130

steel, and pressure controlled means having communication with said feeding means and automatically controlled by pressure changes in said feeding means and effective when an 5 abnormal rate of feeding movement occurs due to a substantial decrease in the resistance to feeding movement for controlling said rotation motor.

12. In combination, a rotation motor, a 10 drill steel rotated thereby, a pressure fluid actuated feeding motor for said steel, and means having communication with said feeding motor and controlled by pressure changes in said feeding motor for automatically varying the operation of said rotation motor.

13. In combination, a rotation motor, a 15 drill steel rotated thereby, pressure fluid actuated feeding means for said steel, and automatic feed pressure controlled means having communication with said feeding means and 20 operable independently of said rotation motor for automatically controlling the speed thereof.

14. In combination, a tool actuating motor, 25 a tool actuated thereby, pressure fluid actuated feeding means for said tool, and means having communication with said feeding means and responsive to pressure changes within said feeding means for automatically controlling said tool actuating 30 motor.

15. In combination, a tool actuating motor, a tool actuated thereby, pressure fluid actuated feeding means for said tool, said feeding 35 means having a fluid supply communicating therewith, and means controlled by pressure changes in said feeding means for automatically controlling said motor including a valve having pressure surfaces and means for 40 subjecting said surfaces to the pressure in said feeding means and said fluid supply, respectively.

16. In combination, a tool actuating motor, a tool actuated thereby, pressure fluid actuated feeding means for said tool, said feeding 45 means having a fluid supply communicating therewith, means controlled by pressure changes in said feeding means for automatically controlling said motor including a valve having pressure surfaces, means for 50 subjecting said surfaces to the pressure in said feeding means and said fluid supply respectively, and means for adjusting the position of said valve.

17. In combination, an independent fluid actuated rotation motor, a drill steel rotated thereby, pressure fluid actuated feeding means for said steel comprising a feed cylinder and a cooperating piston, and means 60 having communication with said feed cylinder and including a pressure actuated valve for automatically controlling the fluid delivered to said motor in accordance with the pressure changes in said feed cylinder.

18. In combination, an independent pres-

sure fluid actuated rotation motor, a drill 76 steel actuated thereby, pressure fluid actuated feeding means for said steel including a feed cylinder and a cooperating piston, and means having communication with said feeding means and responsive to pressure changes in said feeding means for automatically controlling the pressure in said rotation motor.

19. In combination, a rotation motor, a 75 drill steel rotated thereby, feeding means for said steel, and means operatively connected to said feeding means and automatically effective when an abnormal rate of feeding movement occurs due to a substantial decrease in the resistance to feeding movement for controlling the speed of said motor in accordance with the nature of the work 80 encountered by said steel.

20. In combination, work performing means including a tool actuating motor, a 85 tool actuated thereby, a feeding motor for said tool, and means operatively connected to said feeding motor and responsive to the changes of load on said feeding motor for automatically controlling said tool actuating 90 motor.

21. In combination, a tool rotating motor, a tool rotated thereby, pressure fluid actuated feeding means for said tool, and means having communication with said feeding 95 means and automatically controlled by pressure changes in said feeding means for controlling said tool rotating motor.

22. In combination, a tool rotating motor, a tool rotated thereby, feeding means for 100 said tool and means operatively connected to said feeding means and automatically responsive to the changes of load on said feeding means for controlling said tool rotating motor.

23. In combination, a drilling motor, a 105 drill steel actuated thereby, means for rotating said drill steel, feeding means for said steel, and pressure fluid actuated means operatively connected to said feeding means and automatically effective when an abnormal rate of bodily movement of said drilling motor occurs due to a substantial decrease in the resistance to feeding movement for automatically controlling said rotation means.

24. In a drilling apparatus, a drilling 110 motor of the hammer type, a fluid actuated rotation motor, a pressure fluid operated feeding means, and automatic means controlled by pressure changes in said feeding 115 means for supplementing the pressure fluid supply to said rotation motor for increasing the power of the same.

In testimony whereof I affix my signature.
CHARLES F. OSGOOD. 125
